ABSTRACT OF THE DISCLOSURE

In an overload relay employing a primary bimetallic element for tripping the contacts of the relay open in the event of a current overload, the primary bimetal operates upon a motion translator bar which is also acted upon by one leg of a U-shaped ambient temperature compensating auxiliary bimetal; the auxiliary bimetal is mounted by the web of its U to a pivotal mounting which permits pivoting of the bimetal with respect to the housing; upon an increase in the ambient temperature in the housing, the auxiliary bimetal legs deflect outward, and the second leg strikes an abutment on the housing, whereby only the first leg thereof can deflect outward and the deflection of the second leg is absorbed by the pivoting of the auxiliary bimetal around its pivot mounting; upon a decrease in the ambient temperature, the legs of the auxiliary bimetal move inward, until the second leg of the auxiliary bimetal contacts the over center spring of the movable contact operating mechanism; thereafter, the second leg is held stationary while the first leg continues to deflect inward, the deflection of the second leg being absorbed through the pivoting of the auxiliary bimetal around its pivot; upon translation of the translator bar due to deflection of the primary bimetal as a result of an overload, the auxiliary bimetal is pivoted by the movement of the translator bar and the second leg of the auxiliary bimetal strikes and pulling the operating mechanism of the movable contact over center, thereby opening the cooperating contacts.

The present invention relates to an ambient temperature compensated overload relay, and more particularly to such a relay having an auxiliary thermal element for keeping constant the distance a primary thermal element within the relay must travel before it opens the relay control circuit, despite changes in the ambient temperature.

The present invention is used in connection with overload relays of the type shown in U.S. Patent No. 3,226,510 issued to R. W. Thomas, et al., on Dec. 28, 1965, and assigned to the assignee of the instant invention. Such overload relays are, in turn, used in connection with, and to protect, electrical apparatus such as the motor starter shown in U.S. Patent No. 3,324,431, issued June 6, 1967 which is assigned to the assignee of the instant invention. In such overload relays there is a control circuit which is comprised of a stationary contact and of a movable contact, with the latter being mounted on a pivotally mounted arm. The arm forms one leg of a toggle. A biasing means or spring forms the other leg of the toggle. The contact arm can be constructed in such a manner that it is pivoted at a control point and carries the movable contact at one end.

A heater is provided in the vicinity of a primary thermal element which may be a bimetallic strip.

As the i^2t (where i is the amperage and t is the time) through the circuit containing the heater increases, the heat generated by the heater correspondingly increases and the temperature in the vicinity of the thermal element rises correspondingly. The primary thermal element

2

deflects in an amount corresponding to the change in temperature in its vicinity.

A translator bar is provided which is in engagement with the primary element and is moved by the deflection of the thermal element.

5 The movable contact arm, or preferably, the biasing spring, are in engagement with the translator bar in such a manner that movement of the bar over a predetermined distance will cause the movable contact to separate from the stationary contact, thereby opening the control circuit. The biasing spring has a center line position, at which position it is at its greatest extension. When it is moved beyond the center line in one direction, the spring pulls the movable contact away from the stationary contact. When the spring is moved beyond the center line in the opposite direction, the spring snaps the movable contact against the stationary contact. The relay can be calibrated to adjust the position of the center line and thereby to adjust the predetermined distance the biasing spring must be moved before the movable contact is pulled from the stationary contact.

10 As long as the ambient temperature remains constant, the position of the primary thermal element, prior to its deflecting due to a higher level current passing through the heater circuit, will always be the same.

15 However, if the ambient temperature increases, the primary thermal element will have deflected to some extent independent of the temperature of the heater. Since the calibration of the relay is determined by the total heat imparted to the primary thermal element, including the i^2t heat generated in the heater circuit, a lesser increase in the time-current passing through the heater circuit may cause the primary thermal element to deflect a sufficient additional amount, in addition to the deflection due to change in ambient temperature, to cause the movable contact to separate from the stationary one.

20 Similarly, if the ambient temperature decreased, the primary thermal element will have deflected in the opposite direction, independent of the heat generated by the heater. In this case, a greater increase in the time-current passing through the heater circuit will be necessary to cause the primary thermal element to deflect a sufficient amount, when the deflection due to the decrease in ambient temperature is subtracted, to cause the movable contact to separate from the stationary one. Obviously, if the relay is calibrated properly for one ambient temperature, and if the ambient temperature changes, the relay will no longer be properly calibrated.

25 A means is, therefore, needed to ensure that for variation in the ambient temperature, the primary thermal element will deflect the predetermined distance based on a predetermined amount of heat generated by the heater circuit before causing the control circuit to open.

30 The present invention provides an auxiliary thermal element which deflects in response to changes in the ambient temperature and which, by so deflecting, maintains a constant predetermined distance of travel for the primary thermal element to open the control circuit.

35 The auxiliary thermal element of the present invention may be generally U-shaped. The deflecting leg of the U-shaped thermal element engages a formation on the translator bar. The other or non-deflecting leg is positioned near an abutment portion of the relay. The non-deflecting leg of the auxiliary thermal element is the structure which causes the separation of the movable and stationary contacts when it is operated against the biasing means or spring.

40 By employing an auxiliary thermal element, only the increase in the heat or time-current of the heater will be effective to cause the primary thermal element to separate the contacts of the control circuit. Deflection of the primary element due to an increase of the heat generated by

the heater pulls the translator bar, which, in turn, pulls the deflectable leg of the auxiliary element, which is in engagement with the translator bar. The auxiliary element is pivotally secured at the base of its U to the relay housing. As the deflectable leg of the auxiliary element is pulled by the translator bar, the auxiliary element pivots about its support.

The non-deflecting leg of the auxiliary element also pivots and is brought into engagement with the biasing means. Continued deflection of the primary element causes that leg of the auxiliary element to push the biasing means sufficiently to cause separation of the movable contact from the stationary contact.

The auxiliary thermal element may be a bimetallic strip. Since it is U-shaped, its legs deflect in opposite directions in response to variations in ambient temperature. For example, upon an increase in the ambient temperature, the legs of the U deflect outward and upon a decrease in the ambient temperature, they deflect inward.

An increase in the ambient temperature, which would ordinarily cause both legs of the U to move outward, will cause only the leg of the U engaged with the translator bar to move, since the other leg is prevented from moving by the abutment portion of the relay. The outward movement of the leg of the auxiliary element repositions the translator bar. The primary element will have also deflected in response to the increase in ambient temperature. However, since it will have deflected to the same extent that the deflecting leg of the auxiliary element has deflected, looking at the primary element from the vantage point of the translator bar, the primary element will not have deflected at all.

A decrease in the ambient temperature would ordinarily cause both legs of the U to move inward. As the deflecting leg of the auxiliary element moves inward, it draws the translator bar along with it and repositions it. The non-deflecting leg of the auxiliary element moves inward a slight amount until it comes into engagement with the biasing means connected to the movable contact. The biasing means blocks further inward movement of the non-deflecting leg of the auxiliary element. Normally, the force being exerted by the non-deflecting arm on the biasing means might be sufficient to cause the biasing means to move and separate the movable contact from the stationary one. However, the auxiliary thermal element is pivotally mounted at its base to the relay housing. Thus, while the non-deflecting leg is held still by the biasing means, the deflection which would normally take place in the non-deflecting arm is reflected in pivoting of the auxiliary element at the base of its U, which increases the deflection of the deflecting arm of the auxiliary element. The primary element will have deflected in the same direction over the same distance as the deflecting arm of the auxiliary element due to the decrease in the ambient temperature. Hence, looking at the primary element from the vantage point of the translator bar, the primary element will not have deflected at all.

In view of the foregoing, the biasing means will not be affected by the repositioning of its translator bar due to changes in the ambient temperature. Consequently, when the primary thermal element deflects due to a change in the current passing through the heater circuit, the primary thermal element must still be deflected the predetermined distance to move the non-deflecting arm of the auxiliary element the same predetermined distance to cause the separation of the movable and the stationary contacts in the manner set out above.

Thus, this invention ensures that deflection of both the primary and auxiliary thermal elements due to changes in the ambient temperature will not affect the distance the primary thermal element must travel before it will cause the separation of the movable and stationary contacts. Furthermore, the primary element will always deflect a predetermined distance, due to heating of the heater, be-

fore it causes separation of the contacts in the control circuit, regardless of the ambient temperature.

Accordingly, it is a primary object of the present invention to provide an ambient temperature compensated overload relay with a means for compensating for changes in the ambient temperature, thereby ensuring that the control circuit of the relay will not open until a predetermined heat is generated by the heater circuit of the relay.

It is another object of the present invention to provide such an ambient temperature compensated overload relay wherein the auxiliary thermal element, by compensating for changes in ambient temperature, calibrates the relay so that the primary thermal element must always travel a predetermined distance before opening the control circuit.

It is a further object of the present invention to provide such a relay wherein the auxiliary thermal element participates in the opening of the control circuit after a predetermined current passes through the heater circuit.

It is another object of the present invention to provide such a relay where compensation for ambient temperatures is accomplished by repositioning the motion translator bar connecting the primary thermal element and the movable contact of the control circuit.

It is another object of the present invention to provide such a relay wherein the auxiliary thermal element is pivotally mounted and is U-shaped, having a deflecting and a non-deflecting arm, wherein the deflecting arm repositions a translator bar engaged with the primary thermal element due to changes in ambient temperature and the non-deflecting arm is employed to cause the movable contact to separate from the stationary contact.

These and other objects of the present invention will become apparent when the following description is read in conjunction with the accompanying drawings, in which:

FIGURE 1 is a cross-section of an ambient temperature compensated overload relay according to the present invention;

FIGURE 2 is a view of the translator bar used in conjunction with the instant invention viewed in the same direction of view as that of FIGURE 1;

FIGURE 3 is a view in a direction 3-3 of FIGURE 2;

FIGURE 4 is a side view of the auxiliary thermal element shown in FIGURE 1; and

FIGURE 5 is a view of the auxiliary thermal element of the instant invention as viewed in the direction 5-5 of FIGURE 1.

Referring to the drawings, the present invention is used in connection with an overload relay, e.g., of the type described in U.S. Patent No. 3,226,510.

The housing 7 of an overload relay is divided by a wall or dividing structure 8 into a heater chamber 9 and an ambient temperature compensation chamber 10.

Within the ambient temperature compensation chamber is a control circuit, which extends from terminal 11 through terminal strap 12, through movable contact support arm 13, through movable contact 14, through stationary contact 15, through terminal strap 16, and finally through terminal 17. Arm 13 is a rigid element supported at its end 18 in a formation on strap 12 which permits the arm 13 to pivot about its end 18.

Biasing means 19, which is connected by hook 20 at one of its ends to arm 13, and by hook 25 at its other end to support 21, biases contact 14 against contact 15. Biasing means 19 can be a tension spring. There is a center line 22 at which the biasing means is at its greatest extension. If the means 19 is urged in direction A beyond the center line, the means 19 snaps the movable contact 14 open to its dotted line position of FIGURE 1 abutting surface 23 which can be a part of housing 7. The now open movable contact 14 can be moved back into contact with the stationary contact 15 by slide 60 in a manner described in Patent No. 3,226,510.

Adjustment of support means 21, by turning its head 26, causes the means 21 to move alternatively in direction A or in the opposite direction C, since the surface 24 of the means 21 has threads which mesh with a threaded aperture in terminal strap 12. Adjustment of means 21 repositions the center line 22 and adjusts the over center position of arm 13.

When the control circuit is closed, as is shown in solid lines in FIGURE 1, a circuit is closed to, e.g., the starter coil of a motor starter, such as that shown in U.S. Patent No. 3,324,431, issued June 6, 1967; or a signaling device. When the control circuit is opened, the circuit is broken. The opening of the control circuit might automatically or simultaneously close an indicating or a second control circuit in a manner shown in U.S. Patent No. 3,226,510.

Within the heater chamber 9 is a heater 27, which can be configured in any number of ways, as shown in U.S. Patent No. 3,226,510, providing heat to the heating chamber. The heater has terminals 28 and 29 to which leads from the circuit, into which the overload relay is inserted, can be connected, thereby completing a heater circuit.

The control circuit is intended to respond to variations in the i^2t passing through the heater. In the embodiment of the present invention shown in FIGURE 1, the control circuit is designed to respond to an increase in the i^2t through the heater 27 beyond a predetermined threshold valve.

Accordingly, some means is required so that when the time-current relation or heat in the heater 27 reaches a predetermined threshold value, the control circuit will be opened. A primary thermal element 30, which is mounted at its end 31 to a support means 32, as is more fully described in U.S. Patent No. 3,226,510, is provided. The element 30 might be a bimetallic strip comprised of two face-bonded strips of metal having different coefficients of expansion.

In FIGURE 1, the primary element 30 is indirectly heated by the heater 27. An alternate embodiment (not shown) of the present invention has the primary element being directly heated by having the primary element serve as part of the means electrically connecting between terminals 28 and 29.

As shown by the dotted lines in FIGURE 1, when the heat in chamber 9 increases, the free end 33 of element 30 deflects in direction A.

Primary thermal element 30 engages translator bar 40 by abutting surface 41 of projecting ear 42 (see FIGURE 3). The bar 40 will, therefore, move in direction A through the same distance as the free end of element 33.

The bar 40 has in engagement with it the auxiliary thermal element 50 (see FIGURE 4). Auxiliary element 50 is, as can be seen in FIGURE 4, generally U-shaped, having arms 51 and 52. The base 53 of the element 50 is secured to the housing 7 by a support means 54, which permits the element 50 to pivot thereabout in a manner described hereinbelow. The support means 54 might be a hinge or might be comprised of a flexible connecting material. Aperture 57 in the arm 52 of the auxiliary thermal element is provided so that support means 21 can be connected with the biasing means 19 while the means 21 is externally adjustable.

The auxiliary thermal element 50, like the primary element 30, should be so comprised that its arms deflect, due to changes in the ambient temperature. The element 50 can be a bimetallic strip comprised of similar materials and in a similar manner as the primary element 30. As the ambient temperature increases, the element 50 tries to move toward a straight line condition, i.e., the arms 51 and 52 press outward. As the ambient temperature decreases, the arms 51 and 52 deflect inward toward one another.

The notch 43 of the translator bar 40 provides a formation for engaging portion 55 of arm 51 of element 50. Thus, when translator bar 40 moves in direction A in response to deflection in that direction by primary element

30, due to an increase in the amperage in the heater circuit, arm 51 of the auxiliary element is pulled in the same direction. Since the auxiliary element is secured by support means 54, heater-caused movement of the arm 51 causes the entire element 50 to pivot in direction B about its support means 54. This causes arm 52 and its actuating portion 56 to be moved in direction B.

Pivoting actuating portion 56 of auxiliary terminal element 50 engages the biasing means 19 and pushes the same in the direction B. When the biasing means 19 has been pushed over the center line 22, the movable contact 14 snaps open to its dotted line position of FIGURE 1.

The foregoing described the manner in which the heating of the heater 21 causes the separation of the movable contact 14 from the stationary contact 15, thereby opening the control circuit.

A problem can arise in the calibration of the overload relay described above when changes occur in the ambient temperature. Once the positions of the biasing means 19 and of the center line 22 have been set by adjustment of the support means 21, separation of the movable contact 14 from the stationary contact 15 will occur only after the translator bar 40 has been moved a predetermined distance in the direction A. Movement of the translator bar 40 is controlled by deflection of the primary thermal element 30. If, for example, the ambient temperature within the housing 7 has increased, even before the heater 21 has heated up in response to an increase in the current in the heater circuit, the primary thermal element will have deflected a distance in the direction A. Thus, the end 33 of the primary element 30 will have to deflect a shorter distance in the direction A as a result of an increase of the heat generated by the heater 21 before it causes the opening of the control circuit. Obviously, at elevated ambient temperatures, a lesser increase in the current passing through the heater 21 will cause a separation of the contacts in the control circuit than at lower ambient temperatures.

If, on the other hand, the ambient temperature within the housing 7 has decreased, the primary thermal element 30 will have deflected a distance in the direction C. Thus, when the heater 21 has heated up in response to an increase in the current in the heater circuit, the end 33 of the primary element will have to deflect not only the predetermined distance it was calibrated to deflect, but the additional distance that the primary element had previously deflected in direction C due to a decrease in the ambient temperature. Obviously, as the ambient temperature decreases, a greater increase in the current passing through the heater 21 will be required to cause a separation of the contacts in the control circuit than at higher ambient temperatures.

The auxiliary element 50 of the present invention is designed to compensate for changes in the ambient temperature. As was noted above, the arm 51 of the element 50 is positioned within notch 43 of the translator bar 40. The arm 52 of the element 50 is normally positioned between the biasing means 19 and the abutment surface 61 of the terminal strap 12. Neither the arm 52 nor its actuating portion 56 is in engagement with the translator bar 40. This is ensured by the cut-out portion 44 of the translator bar 40.

When the ambient temperature increases, the arm 51 of the auxiliary element deflects in direction A. The arm 52 attempts to deflect in direction C, which is opposite to direction A. However, the abutment surface 61 prevents movement of the arm 52 in direction C. Consequently, the outward movement of the arm 52 is translated into pivotal movement of the base 53 of the auxiliary element 50 about its support 54 in the direction B, which causes the arm 51 to move an additional distance in the direction A.

The materials of which the primary element 30 and the auxiliary element 50 are comprised can be so chosen by one skilled in the art, and the primary and auxiliary

elements can be so positioned, that for every change in the ambient temperature, whether it be an increase or decrease, the deflection of both the end 33 of the primary element 30 and of the leg 51 of the auxiliary element 50 will be in the same direction and will be equal in distance. 5

Deflection of the primary thermal element 30 and of the arm 51 of the auxiliary thermal element 50 due to an increase in the ambient temperature moves the translator bar 40 in the direction A the same distance as each element deflects. However, the arm 52 of the auxiliary 10 thermal element, being in engagement with abutment surface 61, has deflected only minimally. Thus, even after the translator bar 40 has been moved by both thermal elements in response to an increase in the ambient temperature, the bar 40 must still be moved the predetermined distance in order to cause the portion 56 of the auxiliary thermal element to move the biasing means 15 sufficiently to separate the contact 15 from the contact 14. 15

Upon a decrease in the ambient temperature, the arms 51 and 52 of the auxiliary element 50 move toward one 20 another. After the arm 52 has moved a short distance in the direction A, portion 56 will engage the biasing means 19. Further deflection inward of the arm 52 would normally move the biasing means in the direction A and might cause the means 19 to move over the center line 25 22, thereby opening the movable contact 14. However, because of the pivotal mounting of the base 53 on support means 54, instead of the arm 52 continuing to move in the direction A, further deflection in that direction causes the base 53 to pivot in the direction D. The arm 51 of the element 50, meanwhile, is deflecting inward in the direction C. The pivoting of the base 53 in the direction D increases the amount of pivoting done by the arm 51. 30

Due to the pivoting of the base 53, the portion 56 does not bear on the biasing means 19 with sufficient pressure 35 to cause it to move and, therefore, there is no danger that the movable contact will be forced open when the ambient temperature is decreasing.

Movement of the arm 51 in the direction C repositions the translator bar 40. The end 33 of the primary element 40 30 is also deflected in the direction C due to the decrease in the ambient temperature. As was noted above, the materials of the primary and auxiliary elements are so chosen that the distance that the end 33 and that the arm 51 deflects is the same for each decrease in the ambient 45 temperature. Thus, even after the translator bar 40 has been moved by the arm 51 of the auxiliary thermal element in response to a decrease in the ambient temperature, the bar 40 must still be moved the predetermined distance in direction A by an increase in the temperature of the heater 27 in order to cause the portion 56 of the auxiliary thermal element to move the biasing means 19 sufficiently to separate the contact 15 from the contact 14. 50

From the foregoing, it can be seen that the invention has provided a novel thermally actuated overload relay with a control circuit comprising a movable and a stationary contact in which the movable contact will be separated from the stationary contact after there has been a predetermined change in the heat generated by the heater circuit, regardless of the ambient temperature 55 within the relay housing.

Although there has been described a preferred embodiment of this novel invention, many variations and modifications will now be apparent to those skilled in the art. Therefore, this invention is to be limited not by the specific disclosure herein, but only by the appending claims.

The embodiments of the invention in which an exclusive privilege or property is claimed are defined as follows:

1. In an ambient temperature compensated overload relay, said relay comprising:

a housing;

cooperating contacts in a first circuit through said relay; said contacts being within said housing and 70

8 including a relatively stationary and a relatively movable contact; terminals to which said contacts are connected;

a heater which is positioned and adapted to be heated by the i^2t in a second circuit through the overload relay;

a primary bimetal within said housing and positioned with respect to said heater as to be heated when said heater heats up; support means within said housing for mounting said primary bimetal; said primary bimetal having the characteristic that a first end thereof deflects as both the heat generated by the i^2t to the circuit and the ambient temperature increase and decrease;

a translator bar means;

a first formation on said translator bar means; said first end of said primary bimetal being engageable with said first formation as said primary bimetal deflects in a first direction;

an auxiliary bimetal within said housing positioned away from said heater, whereby said auxiliary bimetal can respond to the ambient temperature in said housing without being directly affected by heating of said heater; said auxiliary bimetal including a first and a second leg joined by a web;

a second formation on said translator bar means; said first leg of said auxiliary bimetal being in engagement with said second formation as said auxiliary bimetal deflects, for shifting said translator bar means in response to ambient temperature variation; said translator bar means being linked to said movable contact so that movement of said translator bar means due to deflection of said primary bimetal as a result of an i^2t overload will cause said cooperating contacts to separate;

the improvement comprising,

pivot support means in said housing for supporting said auxiliary bimetal by said web thereof and for permitting said auxiliary bimetal to pivot as described; said web being pivotally supported on said pivot support means therefor;

blocking means in said housing for blocking movement of said second leg of said auxiliary bimetal, whereby deflection of said auxiliary bimetal due to variations in the ambient temperature in said housing causes deflection of said first leg of said auxiliary bimetal and causes pivoting of said web of said auxiliary bimetal about said pivot support means.

2. In the ambient temperature compensated relay of claim 1, said relay further comprising first means for separating said relatively movable contact from said relatively stationary contact, said first means being positioned to be acted upon and being connected with said translator bar means; the improvement further comprising:

said blocking means comprising an abutment surface in said housing when said auxiliary bimetal is deflecting in one direction and comprises said first means when said auxiliary bimetal is deflecting in the opposite direction.

3. In the ambient temperature compensated relay of claim 1, the improvement further comprises, said first means for separating said relatively movable contact from said relatively stationary contact is positioned so as to be engaged by said second leg of said auxiliary bimetal; upon deflection of said primary bimetal due to an i^2t overload and upon corresponding shifting of said translator bar means, said first leg of said auxiliary bimetal being correspondingly shifted by said translator bar means; said pivot support means for said auxiliary bimetal permitting said auxiliary bimetal to pivot thereabout to cause said second leg of said auxiliary bimetal to engage said first means and trip apart said cooperating contacts.

4. In the ambient temperature compensated relay of

claim 3, said first means comprises an over center tension spring stretched between said relatively movable contact and a fixed support on said housing.

5. In the ambient temperature compensated relay of claim 3, the improvement further comprises said blocking means comprising an abutment surface in said housing when said second leg of said auxiliary bimetal is deflecting in one direction, and comprising said first means for separating said relatively movable contact from said relatively stationary contact when said second leg of said auxiliary bimetal is deflecting in the opposite direction.

10 6. In the ambient temperature compensated relay of claim 5, said auxiliary bimetal being U-shaped and having the characteristic of having its legs deflect outward on one of ambient temperature increase and decrease, and deflect inward on the other of the increase and decrease; on said auxiliary bimetal deflecting outward, said second leg thereof contacting said housing abutment surface; and on said auxiliary bimetal deflecting inward, said second leg thereof contacting said first means.

15 7. In the ambient temperature compensated relay of claim 6, said first means comprises an over center tension spring stretched between said relatively movable contact and a fixed support on said housing.

8. In the ambient temperature compensated relay of 25

claim 7, said primary and auxiliary bimetals being constructed and positioned to deflect in the same direction due to variations in temperature;

said auxiliary bimetal being designed whereby the portion of said first leg thereof that engages said translator bar means deflects the same distance as the end of said primary bimetal that engages said translator bar means;

upon an increase in the ambient temperature, said arms of said auxiliary bimetal deflect outward; and upon a decrease in ambient temperature, they deflect inward.
